UNITED STATES PATENT OFFICE.

FRANK JOSEPH McNULTY, OF CLARKDALE, ARIZONA.

RESILIENT WHEEL.

Application filed May 25, 1923. Serial No. 641,460.

To all whom it may concern:

Be it known that I, FRANK J. McNULTY, a citizen of the United States, and resident of Clarkdale, in the county of Yavapai and

5 State of Arizona, have invented certain new and useful Improvements in Resilient Wheels, of which the following is a specification.

10 My invention relates to improvements in resilient wheels, and it consists in the combinations, constructions and arrangements herein described and claimed.

15 More specifically, the present invention is an improvement over the resilient wheel disclosed in Letters Patent of the United States #1,277,330, granted to me August 27th, 1918.

20 An object of the present invention is to improve the construction of resilient wheels of the type described by providing therein a novel construction and arrangement of parts constituting a resilient structure for supporting a tread on the rim of the wheel of conventional construction so that the tread 25 is permitted to move bodily in the general plane of the wheel and to have cushioned movement within fixed limits along radial lines toward and away from the axis of rotation of the wheel, whereby the wear on 30 the tread will be relatively slight.

25 A further object of the invention is to provide in a resilient wheel of the character described a resilient tread supporting structure comprising but relatively few parts 35 and having means for excluding dust and moisture from the contiguous surfaces of the relatively moving parts thereof and for lubricating such contiguous surfaces so that the wear thereon will be relatively slight and 40 the resilient structure will be readily responsive to varying stresses transmitted thereto through the tread to give the desired resiliency and to absorb shocks which would otherwise be occasioned by such 45 stresses.

50 Other objects and advantages will be apparent from the following description, considered in conjunction with the accompanying drawings, in which—

Figure 1 is a side elevation of the portion of a resilient wheel in which the present invention is embodied,

Figure 2 is a vertical section through the structure exhibited in Figure 1 at right

angles to the axis of rotation of the wheel, 55 the section being taken substantially along the line 2—2 of Figure 3,

Figure 3 is a section along the line 3—3 of Figure 2,

Figure 4 is a fragmentary enlarged perspective view showing a slide block and supporting and cushioning means therefor, all such parts being included in the structure shown in the preceding views,

Figure 5 is a transverse section through 65 one of the cushion blocks comprised in the embodiment of the invention, and

Figure 6 is an enlarged fragmentary vertical sectional view, showing a portion of the structure exhibited in Figure 3. 70

75 A practical embodiment of the present invention is illustrated in the drawings and includes an inner rim 1 having on its inner periphery an integral, annular rib 2 adapted to fit upon the rim of a wheel of conventional construction, not shown, between the usual rim flanges, also not shown, the rib 2 being formed to provide annular grooves 3 in its lateral faces adapted for interlocking engagement with the usual beads or inwardly turned outer edge portions of the aforesaid rim flanges. 80

85 A pair of integral, annular flanges 4 extend radially outward from the opposite ends of the rim 1. A plurality of equi-distantly spaced apart guides 5 of substantially inverted V-shape are provided on the outer periphery of the rim 1, the sides of each of these guides being integral at their bases with the rim 1 and integral at their 90 opposite ends with the respective flanges 4.

95 A thin bumper or stop 6 integral with the rim 1 is provided midway between the adjacent ends of each two adjacent guides 5, the respective bumpers or stops 6 lying in planes extending radially from the axis of rotation of the rim and also transversely of the rim, the bumpers or stops 6 terminating with their outer ends in a circle concentric with the rim 1 and substantially coincident 100 with the circle in which the apices of the guides 5 terminate. The bumpers or stops 6 are integral at their lateral ends with the flanges 4.

105 Each of the guides 5 is slightly flattened at its apex as indicated at 7 and the sides of the guides are inclined oppositely from the flat portions 7 to their points of juncture

with the rim 1. A block 8 which may be made of wood, fibre or other relatively incompressible material is disposed on the outer face of each of the inclined sides of each guide in sliding engagement therewith and extends radially beyond the flat portion 7 of the guide, having the outer face thereof curved arcuately to conform to the contour of the inner periphery of an intermediate rim 9 which is supported upon the slide blocks 8 in spaced relation to the flat portions of the respective guides. The blocks 8 are partially received between the flanges 4 and thus are held against lateral movement. 10 A resilient cushioning block 10 is provided between each bumper or stop 6 and the adjacent end of one of the blocks 8. Each cushioning block 10 is made of a material possessing inherent resiliency such as rubber and is formed with an expansion chamber 11 therein provided with open air vents 12 of relatively slight area. Each of the cushioning blocks 10 is provided with a relatively wide annular groove 13 in its outer periphery, which groove is concave in cross sectional contour. A relatively great contraction and expansion of each of the cushioning blocks in the direction of its length therefore is possible. Each cushioning block continuously urges the block 8 with which it is in contact outwardly along the block supporting side of one of the guides 5 and yieldingly resists movement of the block inwardly along the side of the guide, at the same time absorbing shocks and jars which otherwise would be transmitted to the inner rim 1 and thence to the axle of the wheel and the parts supported on the latter. Each block 8 carries on its lateral and inner faces 30 slightly extending pieces of a suitable lubricant, such as graphite, which pieces are inset in the faces of the block in position to contact with the relatively moving portions of the guides 5 and flanges 4. The sliding of the blocks 8 relatively to the guides 5 and the inner walls of the flanges 4 therefore will occasion very little friction and wear on such parts. 40 The intermediate rim 9 is provided at one end with an inwardly extending radial flange 15 engaging with the blocks 8 at one side and thus holding the intermediate rim 9 against movement laterally in one direction relatively to the blocks 8. The intermediate rim 9 is held against lateral movement in the opposite direction through the agency of a retaining ring 16 which is partially disposed in flatwise contiguous relation to an outwardly extending flange 17 at the second end of the rim 9 and which extends inwardly beyond the inner wall of the rim 9 into engagement with the blocks 8 at the sides of the latter opposite to the flange 15. The retaining ring 16 is secured to the outwardly extending flange 17 by

screws or cap bolts 18 which also have an additional function which will be herein-after described.

With the arrangement described the rim 9 and the parts carried thereby which will be presently described are permitted to move bodily in the general plane of the rim 1 toward and away from the axis of rotation of the wheel, inward movement of the rim 9 at any point causing inward movement of the slide blocks 8 against the action of the resilient cushioning blocks 10, while the outward movement of the rim 9 which occurs at the opposite side of the wheel simultaneously with the movement of the rim 9 inwardly at any point will result in the blocks 8 at the side of the wheel at which the outward movement occurs being moved outwardly until the cushioning blocks 10 forcing the slide blocks 8 outward are fully expanded.

As stated, the rim 9 is provided at one end with an outwardly extending flange 17. The latter is provided at its outer edge with a laterally extending ring extension 19 in alignment with an oppositely directed outwardly extending annular portion of a ring extension 20 at the outer end of an outwardly extending annular flange 21 at the opposite end of the rim 9. An outer rim 22 carrying on its outer periphery a tread 23 is mounted adjacent to its opposite ends upon the ring extensions 20 and 19 and is thus maintained in concentric parallel relation to the intermediate rim 9. The tread 23 which may be made of rubber, or a suitable fabric is held against displacement from the rim 22 through the agency of flanges 24 at the ends of the rim 22 in interlocking engagement with the beads at the ends of the tread.

The outer rim 22 is held against displacement from the ring extensions 19 and 20 by an integral flange 25 on the ring extension 19 acting conjointly with a retaining ring 26 secured by a cap bolt 35 to the annular flange 21, the ring 26 having outwardly extending radial lug portions 26^a extending through notches 20^a in the outer edge of the ring extension 20 into position to engage 115 with one of the flanges 24, the other rim flange 24 being engaged by the flange 25.

It is desirable that means be provided for excluding dust, moisture and other foreign matter from the blocks 8 and cushion blocks 10. It of course is essential that such dust excluding means shall not prevent bodily movement of the rim 9 and parts carried thereby relatively to the rim 1. To this end, I provide a pair of annular sealing rings 27 which are made of rubber or like flexible material. The outer diameter of each of the rings 27 is slightly greater than that of the ring extensions 19 and 20 while the inner diameter of each of the rings 27

preferably is slightly less than that of each of a pair of oppositely extending aligned integral ribs 28 on the flanges 4 adjacent to but spaced from the outer edges of the latter. One of the rings 27 is stretched slightly and mounted upon one of the annular ribs 28 so that the outer peripheral wall of such sealing ring is in abutting relation to the inner wall of the ring extension 5 19. The inner edge portion of the sealing ring 27 just mentioned is clamped by a retaining ring 29 and screws or cap bolts 30 against the outer edge portion of one of the flanges 4 while the outer edge portion of 10 the sealing ring 27 is held against the ring 16 by an outer clamping ring 31 which is held in place by the screws 18. The second sealing ring 27 is mounted upon the second annular rib 28 and is clamped adjacent to 15 its inner edge against the outer edge portion of the second flange 4 by a clamping ring 32 and screws or cap bolts 33. The second sealing ring 27 is clamped adjacent to its outer edge against the flange 21 by the retaining ring 26 and screws or cap bolts 35. 20

With the arrangement described, the sealing rings 27 will have substantially spiral gathered portions intermediate their inner and outer edges, as indicated at 36 and a 25 relatively great movement of the rim 9 in respect to the rim 1 therefor will be permitted without subjecting the sealing rings 27 to strain.

The guides 5 may have the walls thereof 30 reinforced by radially extending reinforcing members 37 which are integral with both the sides of the guides and with the rim 1.

The rim 1 preferably includes a plurality of removable plate sections 34, there being 35 a plate section underlying each two adjacent cushion blocks 10 and each plate section normally being held in position to complement the remainder of the rim by a screw 34^a which extends through an opening in the 40 plate section into threaded engagement with a socket in the overlying stop 6. Each plate section 34 normally closes an opening of sufficient area to permit of the overlying cushion blocks 10 being removed there- 45 through when the plate section has been removed without there being any necessity of disassembling the parts of the device which are disposed outwardly of the rim 1.

From the foregoing description of the 50 various parts of the device, the operation thereof may be readily understood. The resilient tread supporting structure described will possess the resiliency required to adapt it for use in wheels for supporting vehicles of various kinds under different service conditions. All parts of the device carried upon the rim 1 and the parts integral with the latter can be displaced for the purpose of replacement or repair. The slide blocks 8 will slide easily on the guides 5.

and since dust and the like are excluded from the space surrounding the slide blocks and the slide blocks and the parts moving relatively thereto are kept lubricated in the manner described, the wear on such relatively moving parts will be slight. 70

Therefore it will be apparent that I provide a resilient mechanical structure which is adapted to be mounted on the rim of a wheel of ordinary construction to provide all 75 the advantages of a pneumatic tire without possessing the objectionable features of the latter.

As best seen in Figure 2, the tread carrying rim 22 may be supported intermediate its 80 ends on spaced apart radial fins 38 provided on the outer periphery of the rim 9 to extend across the latter, the fins 38 terminating at their outer ends flush with the outer faces of the ring extensions 19 and 20. 85

Obviously, my invention is susceptible of embodiment in forms other than that illustrated in the accompanying drawings and I therefore consider as my own all modifications and adaptations of the form of the device illustrated herein which fall within the scope of the appended claims. 90

I claim:—

1. In a resilient wheel, an inner rim adapted to be mounted on the rim of a conventional wheel, a second rim resiliently spaced and held in concentric encircling relation to the inner rim, flexible sealing rings adapted to seal the space between said rims at the ends of the latter, each of said sealing rings having substantially spiral gathered portions intermediate the inner and outer edges thereof, and annular retaining members for securing the edge portions of each sealing ring to the respective 100 rims. 95

2. In a resilient wheel, an inner rim having a plurality of spaced apart outwardly extending substantially inverted V-shaped radial guides on its outer periphery and having an outwardly extending radial stop on its outer periphery midway between each two adjacent guides, a second rim adapted to be disposed in encircling concentric relation to said inner rim in spaced relation to 110 the apices of said guides, a pair of slide blocks on each guide, the respective slide blocks of each pair being in sliding engagement with the outer faces of the sides of the guide, said blocks extending radially outward beyond the apices of the guides and having their outer faces curved to conform to the curvature of the inner periphery of the second rim, and resilient cushion blocks disposed between the remote ends of the 115 blocks of each pair and the adjacent stops for urging the blocks of each pair toward each other and outward into engagement with the inner periphery of the second rim. 120

3. In a resilient wheel, an inner rim hav- 130

- ing a plurality of outwardly extending spaced apart substantially inverted V-shaped guides on the outer periphery thereof and having a pair of outwardly extending marginal flanges flanking said guides, slide blocks disposed in sliding engagement with the sides of the guides and with the inner faces of said flanges, said slide blocks extending radially outward beyond the apices of said guides and having the outer faces thereof convexly curved, a second rim encircling said inner rim, resilient cushioning means urging said slide blocks outward on the guides into engagement with the inner periphery of said second rim, said cushioning means comprising a plurality of rubber blocks, each having one end reacting against the inner end of one of said slide blocks and each having an interior expansion space therein provided with an air vent, each of said cushion blocks having an annular groove convexly curved in cross sectional contour in its outer wall intermediate its ends.
25. 4. In a resilient wheel, an inner rim having a plurality of spaced apart outwardly extending substantially inverted V-shaped radial guides on its outer periphery and having a normally closed opening located midway between each two adjacent guides, a second rim adapted to be disposed in encircling spaced relation to said inner rim, a pair of slide blocks on each guide, and resilient cushion blocks disposed between adjacent pairs of slide blocks and urging the slide blocks outwardly on the guides into

engagement with the inner periphery of the second rim, said cushion blocks being adapted to be moved from the inner rim inwardly through the openings through the walls thereof when the closures of said openings have been removed.

5. In a resilient wheel, an inner rim including a plurality of circumferentially spaced inwardly removable plate sections, thus providing openings through the peripheral walls of the inner rim when the plate sections thereof have been removed, and having outwardly extending integral radial stops on its outer periphery, each of said stops extending transversely across one of said removable plate sections and being separate therefrom, devices for securing the respective plate sections to the corresponding stops, said inner rim also having on the outer periphery thereof a substantially inverted V-shaped guide located between each two adjacent stops, slide blocks disposed on the guides for supporting a second rim in spaced relation to the first rim, and a pair of resilient cushion blocks respectively disposed on opposite sides of each stop and between the latter and the adjacent slide blocks for urging the latter outwardly on said guides, each pair of cushion blocks being removable from the inner rim through one of the openings provided through the walls of said rim when one of said removable sections of the rim has been removed.

FRANK JOSEPH McNULTY.
